MUSICAL INSTRUMENT

Borrah Minevitch, New York, N. Y.

Application June 29, 1934, Serial No. 733,009

19 Claims. (Cl. 84—378)

This invention relates to musical instruments, and more particularly to harmonicas or mouth organs, the present invention being an improvement upon that disclosed in my copending application

Serial No. 684,571, filed August 10, 1933, now Patent No. 2,000,408, granted May 7, 1935.

In said copending application, I have shown and described a harmonica of which the casing or cover plates are hinged together at one end of the instrument and are so arranged that they may be removed from the harmonica body to permit cleaning and adjustment of the reeds. Although a construction of this sort is satisfactory, it is relatively expensive of manufacture since it necessitates a plurality of parts and a relatively great number of steps in assembling.

The primary object of my present invention is to provide an improved harmonica casing which will be simple in construction and inexpensive of manufacture.

More specifically, it is an object of my invention to provide an improved and simplified harmonica casing which can be readily removed from the harmonica body with great facility to permit access to the reeds and other parts thereof for cleaning and adjustment purposes, and which can be readily attached to the harmonica body with equal facility.

Another object of my invention is to provide an improved harmonica of the type set forth of which the casing will be comprised of a minimum number of parts consistent with a sturdy construction.

Still another object of my invention is to provide an improved harmonica casing which, although greatly simplified in construction, will, nevertheless, snugly and accurately fit the harmonica body and give to the instrument the finished and pleasing appearance of a high grade instrument.

A further object of my invention is to provide an improved harmonica which will be characterized by the absence of any rough or sharp edges and which will present to the mouth of the player a smooth, continuous mouthpiece.

Still a further object of my invention is to provide an improved harmonica wherein the mouthpiece and casing are so inter-related as to provide a tight joint therebetween so that leakage of air at this point, a disadvantage of many prior art harmonicas, will be practically eliminated.

It is another object of my invention to provide an improved harmonica which will be highly efficient in use and which will have a rela-

tively long life by reason of the ease with which its operating parts can be reached for cleaning and adjusting purposes as well as for any other necessary care.

In accordance with my present invention, I form the casing of a pair of cooperable members which fit around the ends of the harmonica body and which are provided, at their ends, with suitably offset portions adapted to be engaged by a keeper or locking member. The keeper is so arranged as to tightly draw the casing members around the harmonica by reason of its vise-like action, wherefore the casing fits the body in a snug manner. Of the many forms which my invention may take, some may be used without any screws, bolts, or other securing members, while others require but a single screw to secure them in place. When it is considered that prior art harmonicas invariably require a number of screws or the like to keep the casings in place and even then fail to have casings which snugly and accurately fit the body at all times and which are easily removable from the body, the advantages of my invention will be further apparent.

The novel features that I consider characteristic of my invention are set forth with particularity in the appended claims. However, the invention itself, together with additional objects and advantages thereof, will best be understood from the following description of several embodiments thereof when taken in connection with the accompanying drawing in which

Figure 1 is an end elevation of one form of my invention.

Figure 2 is a sectional view on the line II—II of Figure 1.

Figure 3 is a fragmentary exploded perspective of the same form of my invention,

Figure 4 is an end elevation of another form of my invention, and

Figure 5 is a fragmentary exploded perspective of the form of my invention shown in Figure 4.

Referring more in detail to the drawing, wherein similar reference numerals indicate corresponding parts throughout, there is shown, in Figures 1, 2 and 3, a harmonica body or sounding board 1 provided with the usual air passages 2 and to which are attached the reed supporting plates 3 in any suitable manner. A mouthpiece 4 having a plurality of openings 5 therein which register with the air passages 2 is attached to the body 1 by means of screws or equivalent devices 6 and is provided with a

downwardly extending tab 7 at each end and with downwardly turned marginal edge portions 8 for a purpose hereinafter described.

The body 1 is encased within a pair of casing members or plates 9 which diverge from the mouthpiece 4 toward the base of the harmonica, being spaced from the body 1 by the spacing members 10 to provide air passages 11 through which air may be either blown or drawn as the instrument is played. The upper longitudinal edge of each casing member is turned inwardly, as at 12, to fit under the adjacent downwardly-turned marginal portion 8 of the mouthpiece, while the lower longitudinal edges 13 of the casing members are turned inwardly for the reception of tone modifiers of the type and in the manner fully disclosed in my aforesaid co-pending application but which are immaterial to the present invention.

Each end portion 14 of both casing members is bent substantially at right angles to the intermediate portion thereof to extend around the ends of the body 1, adjacent end portions lying in substantially contiguous, or side-by-side, relation. The end portions are cut away at 15 to accommodate the tabs 7 and are formed with offset portions of any desired configuration to be engaged by a suitable keeper member for interconnecting the casing members 9 to the body 1. In the specific embodiment illustrated in Figures 1, 2 and 3, the offset portions are constituted by inwardly pressed grooves 16 and 17, one in each of two adjacent end portions 14, the two grooves 16 and 17 being complementary to each other to form the desired configuration and being shown arcuate in this specific embodiment to form substantially an oval. The keeper member is shown at 18 and is constituted by a substantially oval-shaped plate having a peripheral flange 19 of substantially the same contour and dimensions as the combined grooves 16, 17 and an aperture 20 for the reception of a screw 21 by means of which the keeper 18 may be releasably secured to the body 1 in operative relation to the casing members 9.

In assembling the casing members 9 and the body 1, the longitudinal edges 12 of the casing members are first inserted under the downwardly turned edges 8 of the mouthpiece 4 and the end portions 14 are then slipped over the ends of the body 1, the two casing members being pressed into close interfitting relation with the mouthpiece. Since the edges 12 fit closely under and against the edges 8 and the tabs 7 are snugly accommodated by the cut-out portions 15, a tight joint all around is insured between the mouthpiece 4 and the casing members 9, and leakage of air is thus reduced to a minimum. At the same time, the rounded, closely-interfitting edges 8 and 12 present a smooth lip engaging surface to the player's mouth.

If desired, the end portions 14 may be so formed that the distance between the two end portions of any one casing member will initially be slightly less than the length of the body 1. This will permit a frictional fit of the casing members 9 on the body 1 and will further insure a snug fit between the casing members, the body, and the mouthpiece. In any event, after the casing members have been mounted in place on the body in the manner set forth above, the keepers 18 are applied thereto, one at each end of the harmonica, with the flange 19 of each keeper extending into the slots 16, 17 whereupon the respective screws 21 are advanced

through the openings 20 into the body 1 and the assembling operation is completed. To remove the casing members from the body, it is merely necessary to remove the screws 21 at each end of the harmonica, whereupon the keepers 18 are freed from the grooves 16, 17, and the casing members 9 may then be pried loose from the body 1 in a quick and facile manner.

In the modification of my invention shown in Figures 4 and 5, the casing members are formed similarly to those described above, except that the end portions 14 thereof are offset by having the extreme ends 30 thereof reversely bent on themselves in an outward direction so that contiguous or adjacent ends 30 extend away in opposite directions from each other and in slightly spaced relation to their respective end portions 14. The ends 30 are also so formed that they diverge from each other, being preferably closest together adjacent the mouthpiece tabs 7 and widest apart at the base of the harmonica for a purpose presently to be set forth.

A keeper member 31 provided with inwardly-directed, reversely-bent edge portions 32 serves to releasably lock the casing members 9 of Figures 4 and 5 to the body 1 of the harmonica by engagement of the inwardly-directed edges 32 thereof with the outwardly-directed ends 30 of the casing members. The keeper member 31 is wedge-shaped and of slightly smaller transverse dimensions than the distance between corresponding parts of the ends 30, although generally similar thereto in configuration in that the edges 32 have the same diverging angular relation as the ends 30. Thus, as the keeper 31 is slid over the ends 30, it draws the casing members 9 tightly together and snugly around the body 1. Preferably, the keeper 31 is made of resilient metal and a locking lug 33, provided with a depressed button 34, is struck out therefrom so that the button 34 may engage a depression 35 in the body 1 for releasably securing the keeper to the body in a positive manner.

To assemble the last described modification of my invention, the casing members 9 are first applied to the body 1 in the same manner as described above in connection with Figures 1 to 3. The keepers 31, one at each end of the harmonica, are then slid over the ends 30 until the button 34 engages the respective depressions 35, whereupon the assembling operation is completed. By merely sliding the keepers 31 off at each end, the casing plates are released from locked relation with the body and may be easily removed to obtain access to the inner parts of the instrument. As noted heretofore, the edges 30 are preferably closest together adjacent the tabs 7 so that there will be no danger of the keepers 31 sliding off under the influence of gravity should they become loose for any reason, as would be the case if the edges 30 were closest together at the base of the harmonica. Accordingly, a close fit of the casing members 9 on the body 1 is always assured.

Although I have shown and described several embodiments of my invention, it will be apparent that many other modifications thereof are possible. I desire, therefore, that my invention shall not be limited except insofar as is necessitated by the prior art and by the spirit of the appended claims.

I claim as my invention:

1. In a harmonica, a body, a pair of casing members encasing said body, and means exterior of the body interconnecting said casing members

- for releasably locking said members to said body.
2. In a harmonica, a body, a pair of casing members encasing said body, and means exterior of said body and separable from said casing members interconnecting said members for releasably locking said members to said body.
3. In a harmonica, a body, a pair of casing members encasing said body, the end portions of said casing members extending around the ends of said body into substantially contiguous relation and being provided with offset portions, and means engaging said offset portions and interconnecting said casing members for releasably locking said members to said body.
4. In a harmonica, a body, a pair of casing members encasing said body, the end portions of said casing members extending around the ends of said body into substantially contiguous relation and being provided with grooves, and means engaging said grooves and interconnecting said casing members for releasably locking said members to said body.
5. In a harmonica, a body, a pair of casing members encasing said body, the end portions of said casing members extending around the ends of said body into substantially contiguous relation and being provided with offset portions, means engaging said offset portions for releasably locking said members to said body, and means for releasably securing said locking means to said body in operative relation to said casing members.
6. In a harmonica, a body, a pair of casing members encasing said body, the end portions of said casing members extending around the ends of said body into substantially contiguous relation and being provided with offset portions, means engaging said offset portions and interconnecting said casing members for releasably locking said members to said body, and means independent of said locking means for releasably securing said locking means to said body in operative relation to said casing members.
7. In a harmonica, a body, a pair of casing members encasing said body, the end portions of said casing members extending around the ends of said body into substantially contiguous relation and being provided with offset portions, means engaging said offset portions and interconnecting said casing members for releasably locking said members to said body, and means integral with said locking means for releasably securing said locking means to said body in operative relation to said casing members.
8. In a harmonica, a body, a pair of casing members encasing said body, the end portions of said casing members extending around the ends of said body into substantially contiguous relation and being provided with grooves of predetermined configuration, and means of like configuration fitted within said grooves and interconnecting said casing members for releasably locking said members to said body.
9. In a harmonica, a body, a pair of casing members encasing said body, the end portions of said casing members extending around the ends of said body into substantially contiguous relation and being provided with grooves of predetermined configuration, a keeper member having a flange of like configuration fitted within said grooves and interconnecting said casing members for releasably locking said members to said body, and means for releasably securing said keeper member to said body in operative relation to said casing members.
10. The invention set forth in claim 9 characterized in that the grooves in each of the adjacent casing member end portions constitute complementary parts of said predetermined configuration, and characterized further in that said keeper member has the same configuration and the flange thereon is formed along the periphery thereof.
11. The invention set forth in claim 9 characterized in that the grooves in each of the adjacent casing member end portions constitute complementary parts of substantially an oval, and characterized further in that said keeper member is substantially oval-shaped and the flange thereon is formed along the periphery thereof.
12. In a harmonica, a body, a pair of casing members encasing said body, the end portions of said casing members extending around the ends of said body into substantially contiguous relation, the extreme ends of said casing members being reversely bent on themselves in opposite directions and in spaced relation to said end portions, and means interconnecting adjacent reversely bent ends for releasably locking said casing members to said body.
13. In a harmonica, a body, a pair of casing members encasing said body, the end portions of said casing members extending around the ends of said body into substantially contiguous relation, the extreme ends of said casing members being reversely bent on themselves in opposite directions and in spaced relation to said end portions, means interconnecting adjacent reversely bent ends for releasably locking said casing members to said body, and means for releasably securing said interconnecting means to said body in operative relation to said casing members.
14. In a harmonica, a body, a pair of casing members encasing said body, the end portions of said casing members extending around the ends of said body into substantially contiguous relation, the extreme ends of said casing members being reversely bent on themselves in opposite directions and in spaced relation to said end portions, means interconnecting adjacent reversely bent ends for releasably locking said casing members to said body, and means integral with said interconnecting means for releasably securing said interconnecting means to said body in operative relation to said casing members.
15. In a harmonica, a body having a depression therein, a pair of casing members encasing said body, the end portions of said casing members extending around the ends of said body into substantially contiguous relation, the extreme ends of said casing members being reversely bent on themselves in opposite directions and in spaced relation to said end portions, means interconnecting adjacent reversely bent ends for releasably locking said casing members to said body, and means struck out from said interconnecting means and engaging said depression for releasably securing said interconnecting means to said body in operative relation to said casing members.
16. In a harmonica, a body, a pair of casing members encasing said body, the end portions of said casing members extending around the ends of said body into substantially contiguous relation, the extreme ends of said casing members being reversely and outwardly bent on themselves in opposite directions and in spaced relation to said end portions, and a slidably

keeper member having inwardly-directed, reversely-bent edge portions cooperatively engaging said reversely-bent ends of adjacent casing member end portions for releasably locking said casing members to said body.

17. The invention set forth in claim 16 characterized in that adjacent reversely-bent casing member ends diverge from each other in a direction transverse to the casing members, and
10 characterized further in that said keeper member has a correspondingly diverging, wedge-shape, longitudinal configuration whereby, when said keeper member is slid over said reversely-bent ends into operative position, the keeper member draws said casing members snugly around said body.

18. The invention set forth in claim 16 characterized in that adjacent reversely-bent casing member ends diverge from each other from the

mouthpiece of the harmonica toward the base of the body thereof, and characterized further in that said keeper member has a correspondingly diverging, wedge-shape, longitudinal configuration whereby, when said keeper member is slid over said reversely-bent ends into operative position, the keeper member draws said casing members snugly around said body. 5

19. In a harmonica, the combination of a body, a mouthpiece secured thereto, a pair of 10 casing members interfitting with said mouthpiece, said casing members encasing said body and having their end portions extending around the ends of said body, and means exterior of said body and separable from said 15 casing members for maintaining said casing members snugly around said body and in close interfitting relation with said mouthpiece.

BORRAH MINEVITCH.
